George P. Carroll

UNITED STATES PATENT OFFICE.

GEORGE P. CARROLL, OF HARTFORD, CONNECTICUT.

CONTROLLING MEANS FOR FLUID-CIRCULATING APPARATUS.

Application filed January 17, 1918. Serial No. 212,263.

To all whom it may concern:

Be it known that I, GEORGE P. CARROLL, a citizen of the United States, residing at Hartford, in the county of Hartford and State of Connecticut, have invented a new and useful Controlling Means for Fluid-Circulating Apparatus, of which the following is a specification.

My invention relates especially, but not exclusively, to means for controlling the operation of apparatus that circulates a fluid employed for refrigerating purposes; and in part it relates to means for controlling the operation of all kinds of apparatus that draw in any vaporous or gaseous fluid at low pressure, compress it and force it into a condenser where the heat of compression is carried away, with or without a resulting liquefaction of the fluid. As herein used, the term condenser comprises all of the vessels leading from the discharge valve of the compressor or other compressing means and containing the fluid under high pressure, whether in a liquefied or in a non-liquefied state. For convenience, a very simple form of condenser is herein shown.

The purpose of my invention in part is to provide simple, compact and reliable means whereby predetermined temperatures may be maintained in a plurality of compartments, in part is to economize the operating power of the fluid circulating means, in part is to regulate the capacity of certain fluid circulating means according to head pressure conditions, in part is to secure such regulation for refrigerant fluid circulating means according to temperature requirements, in part is to provide simple and economical means for regulating the flow of condenser cooling water and in part is to provide simple, safe and efficient elements of construction for all such fluid circulating apparatus. The means for accomplishing these purposes will be hereinafter set forth. Certain detail improvements of construction will also so appear. My invention will be particularly disclosed in connection with a machine circulating ammonia as a refrigerant, this being a construction typical of all.

In the drawings, Fig. 1 is a diagrammatic representation of one form of my invention. Fig. 2 is a plan view of the right end of the lever 36 shown in Figs. 1 and 4 and of the lever 36^a shown in Fig. 3, and of their respective connections, broken away. Fig. 3 in part is a representation, partially

in front elevation and partially in vertical section, of part of the structure of Fig. 1 and in part is an alternative construction for a portion of that structure. Fig. 4 is a partial front elevation and a partial vertical section of part of the structure of Fig. 1. Fig. 5 is a front elevation of part of the master refrigerator thermostat shown in Fig. 3. Fig. 6 is a partial front elevation and a partial vertical section of a subordinate refrigerator thermostat shown in Fig. 1, with its connections. Fig. 7 is a diagrammatic representation of the windings and wire connections of an electric motor adapted for use in connection with the structure of Fig. 3. Fig. 8 is a diagrammatic representation of certain wire connections that may be used, by way of alternative construction, in place of certain other wire connections shown in Fig. 3. Fig. 9 is a front elevation of a reservoir and float device that may be used, by way of alternative construction, in place of a certain other construction shown in Figs. 1 and 3. Fig. 10 represents a transposition of certain parts shown in Fig. 1.

First considering Figs. 1, 2, 4 and 6 and a part of Fig. 3: A condenser tank 1, provided on top with a gage 2, has water piping 3, leading downward from a point above the tank into the lower part of the tank, coiling upward therein, emerging from its upper part and discharging downwardly therefrom. A compressor discharge pipe 4 leads upward, thence to the right and thence downward into the top of the tank 1. From the under side of the tank 1 a liquid refrigerant pipe 5 leads to the left. A pipe 6 of small diameter connects the top of the tank 1 with the lower end of a shallow casing 7, provided, as shown in Figs. 3 and 4, with diaphragm stops 8 and enclosed on top by a diaphragm 9, preferably of very thin vanadium steel. The parts 1-9 represent a condenser, including water piping therefor, which may be a double pipe counter current condenser, an atmospheric condenser or any other kind of condenser. An automatic safety or relief valve 10 is connected with the highest part of the pipe 4 and is adapted to discharge into the atmosphere. For ammonia, the discharge limit may be 300 pounds; but the best considered safety regulations in cooler latitudes are now requiring such a valve to begin to open at a pressure of 250 pounds and to be fully open at a pressure of 275 pounds.

A pipe 11 leads into the lower left side of a reservoir casing 12. From the lower right side of the casing 12 a smaller horizontal pipe 13 leads into the left side of a valve casing 14, provided with a vertical valve seat 15 and discharging downward into the top of the piping 3. Surrounding and covering an opening in the top of the casing 12 is an expanding and contracting 5 cylindrical bellows 16, with an undulated or zigzagged circumferential side wall and a flat head. The bellows 16 may be of brass or copper, or it may be of vanadium steel, copper plated or silver plated or otherwise 10 protected against corrosion; and, if constructed of any such material, of a suitable thickness, it is sensitive to pressure changes so as to permit the head to move up or down along the line of the axis. The parts 11—16 15 constitute one form of water reservoir draining into the piping 3 and may be of any necessary or proper capacity.

A clapper valve 17, adapted to close the seat 15, is secured at the top within the casing 14 to the front end of a shaft 18 that extends through the back wall of the casing. Secured to the rear and outside end of the shaft 18 is a short lever 19, extending horizontally to the right. A light 20 compression spring 20 at its lower end bears upon a bracket projecting to the right from the casing 14 and at the top bears upward against the under side of the outer end of the lever 19. A headed bolt 21 is adapted to be 25 screwed up or down in a threaded vertical opening through the lever 19 and is secured in any desired position by a locknut 22, just above the lever. The tendency of the spring 20 is to press upward upon the lever 19 so as 30 fully to open the valve 17. When the valve 17 is fully open, there is a maximum flow of water permissible through the casing 14. But, upon a pressing down of the bolt 21, the valve 17 begins to close, and, if fully 35 closed, it prevents any flow through the casing 14.

The diaphragm 9 near its circumference rests upon a ring at the top of the casing 7 and at its circumference rests upon an annular gasket 23, preferably of soft lead, lying on the downwardly sloping rim of the casing just outside the ring. The stops 8 are intended to prevent an excessive downward movement of the diaphragm 9. It is to be 40 understood that in Fig. 3 the lowest position of the diaphragm 9, when the parts are assembled, by reason of the positioning of the stationary parts, is a little above the stops 8, as shown; and that in Figs. 1 and 4 45 the lowest position of the diaphragm is upon the stops, as shown in the latter figure. There are passages between the stops 8 so that fluid under pressure may be transmitted back and forth between the space under the 50 diaphragm 9 outside of the stops and the

pipe 6. An upper casing 24 has a flange that fits over so much of the diaphragm 9 as rests upon the casing 7 and the gasket 23 and it has at its extreme circumference an annular tongue enclosing the outer vertical surfaces 70 of the diaphragm and the gasket. By means of bolts 25 the casings 7 and 24 are clamped together at their circumferences and press the edge of the diaphragm 9 and the gasket 23 between the casings. The casing 24 has 75 in its under side a shallow chamber of equal diameter with the chamber in the top of the casing 7; it has at its axial center a cylindrical chamber extending upward from the shallow chamber nearly to the top; it has 80 a small threaded passage at its axial center extending through the top; and it has a space at the lower right side of the cylindrical chamber from which a horizontal shaft passage extends through the rear wall. A reciprocating member 26 has a flange at the lower end resting upon the center of the diaphragm 9 and of a diameter greater than that of the stops 8; above its flange it is 85 adapted to reciprocate within the lower end 90 of the cylindrical chamber in the casing 24; and it has in the part so reciprocating a transverse passage extending from left to right. The upward movement of the member 26 would be limited, in case of an extremely high pressure on the under side of the diaphragm 9, by its flange striking the wall of the casing 24 around the lower end 95 of the cylindrical chamber therein. A heavy compression spring 27 occupies the upper 100 end of the cylindrical chamber in the casing 24 and it bears, at the lower end, upon the top of the member 26 and, at the upper end, upon the head of a bolt 28 passing upward through the passage in the top of the casing 105 24. The end of the bolt 28 above and outside the casing 24 has a square wrench section whereby the bolt may be turned up or down and it is held in any desired position by a lock nut 29 just above the top of 110 the casing. It is evident that, upon loosening the nut 29, the bolt 28 may be screwed downward so as to increase the thrust of the spring 27, or it may be screwed upward so 115 as to decrease the thrust. A cap 30 screws around the threaded top of the casing 24, which is of reduced diameter, and over the nut 29 and the exposed end of the bolt 28. A wire 31 is passed through holes in two 120 lugs projecting to the right from the cap 30 and the casing 24, respectively, and is sealed after the bolt 28 and the nut 29 have been 125 adjusted as desired. A rock shaft 32 is journaled at its rear end in the front end of a support 33; it enters the rear wall of the 125 casing 24 through a stuffing box gland nut 34; and it has secured to its front end within the casing a short lever 35 that has its free end within the recess of the member 26. In 130 Figs. 1 and 4 a long lever 36 is secured to

the shaft 32 between the nut 34 and the support 33 and at its upper end it tends to bear upon the head of the bolt 21. The parts 24—36 constitute one form of controller. In Fig. 5 3 a long lever 36^a is secured to the shaft 32 between the nut 34 and the support 33, at its outer end it tends to bear upon the head of the bolt 21 and near its outer end it carries a transverse conductor 36^b, insulated from 10 the main part of the lever. The parts 24—35, 36^a and 36^b constitute another form of controller.

With the stationary parts positioned as shown in Fig. 3, in the absence of a countervailing pressure on the under side of the diaphragm 9, the spring 27 bears downward upon the member 26 so that the parts 35, 32, 36^a, 36^b, 21, 22, 19 and 18 are so turned that the valve 17 completely closes 20 the seat 15 and prevents any water whatsoever from flowing through the casing 14. Then, after such complete closing, when the pressure on the under side of the diaphragm 9 exceeds the thrust of the spring 27, the lever 36^a is lifted upward and the spring 20 forces the bolt 21 to follow the lever so that the valve is gradually opened more and more and finally to its full limit, if the lever is lifted far enough. With the stationary 25 parts positioned as shown in Fig. 4, the positioning thereof in Fig. 1 being the same, in the absence of a countervailing pressure on the under side of the diaphragm 9, the spring 27 bears downward upon the member 26 so 30 that the parts 35, 32, 36, 21, 22, 19 and 18 are so turned that the valve 17 never entirely closes the seat 15 and thus always permits an escape of water from the casing 14, thus resembling the construction disclosed in my 35 40 aforesaid applications Ser. No. 126,019 and Ser. No. 146,147. Then, after such partial closing, when the pressure on the under side of the diaphragm 9 exceeds the thrust of the spring 27, the lever 36 is lifted upward and the spring 20 forces the bolt 21 to follow the lever so that the valve is gradually opened yet more and more fully and finally to its full limit, if the lever is lifted far enough. 45

Leading into the inlet end of the pipe 11 50 is an electrically operated means 37 for controlling a flow of cooling water to the reservoir composed of the parts 11—16, the inlet end of the means being connected to a source of cooling water, not shown. The particular means indicated is the electric valve disclosed in the patent issued to me on the application of Roehrich, No. 959,609, dated May 31, 1910, having a construction such that upon an instantaneous energization of 55 60 a magnet winding 21^x thereof the valve is opened to the full limit and upon an instantaneous energization of a magnet winding 40^x thereof the valve closes. The capacity of the means 37 and of all passages 65 leading thereto must be such, and the pres-

sure of the transmitted water must be such, that, when water is flowing therethrough, the reservoir composed of the parts 11—16 will be completely filled and the bellows 16 will be lifted to its highest limit even although the valve 17 is wide open and the passages leading therefrom are transmitting the full flow of water permitted by the valve being so open.

Leading from the outlet end of the pipe 75 5 is an electrically operated feed valve 38, being the valve disclosed in said Patent No. 959,609, having a construction such that upon an instantaneous energization of a magnet winding 21^y thereof the valve is 80 opened to the full limit and upon an instantaneous energization of a magnet winding 40^y thereof the valve closes. A T 39 is connected with the outlet end of the valve 38 and from one outlet of the T 39 a feed pipe 85 40 leads through the wall of a master compartment 41 and to an automatic expansion valve 42. The valve 42 and the similar valves 50 and 56, to be indicated, may be of the construction disclosed either in the 90 patent to me No. 906,508, dated Dec. 15, 1908, or in the patent to me upon the application of Roehrich and myself, No. 1,137,051, dated Apr. 27, 1915. Within the compartment 41 is a master expansion chamber 43, also called an 95 evaporator or expansion coil, leading from the valve 42, having its coils within the compartment and leading outward through the wall of the compartment to a T 44. A T 45 is connected with the other outlet of the T 100 39 and from one outlet of the T 45 a feed pipe 46 leads through the wall of a compartment 47 and to a valve casing 48. From the casing 48 a pipe 49 leads to an automatic expansion valve 50, similar to the valve 42. 105 Within the compartment 47 is an expansion chamber 51, leading from the valve 50, having its coils within the compartment and leading outward through the wall of the compartment to the T 44, thus being in 110 parallel with the expansion chamber 43. From the other outlet of the T 45 a feed pipe 52 leads through the wall of a compartment 53 to a valve casing 54. From the casing 54 a pipe 55 leads to an automatic expansion valve 56, similar to the valve 42. 115 Within the compartment 53 is an expansion chamber 57, leading from the valve 56, having its coils within the compartment and leading outward through the wall of the 120 compartment into that part of the expansion chamber 51 that has emerged from the compartment 47. Consequently so much of the expansion chambers 43, 51 and 57 as are within the compartments 41, 47, and 53, 125 respectively, are in parallel with one another. For convenience of illustration the compartments 41, 47 and 53 are indicated as being of the same size. So, also, the part of the expansion chamber 51 that is within 130

the compartment 47 is longer than the part of the expansion chamber 43 that is within the compartment 41 and the part of the expansion chamber 57 that is within the compartment 53 is longer than the part of the expansion chamber 51 that is within the compartment 47. In practice the feed valve 38 is placed as near as practicable to the compartments 41, 47 and 53.

10 Within the casing 48, as shown in Fig. 6, is a valve seat 58 adapted to be closed from beneath by a conical valve 59, the stem of which extends upward through the valve seat. A flanged top 60 surrounds the upper 15 part of the stem of the valve 59 and is screwed into a threaded opening in the upper part of the casing 48. A disc 61 is detachably secured to the upper end of the stem of the valve 59 and is adapted to reciprocate a short distance in a shallow chamber within the flange of the top 60 sufficiently to permit of the opening and closing of the valve 59. Within the top 60, at its axial center and below its shallow chamber, is a 20 vertical chamber containing a compression spring 62 that bears upward upon the disc 61 so as to tend to close the valve 59. A diaphragm 63, preferably of vanadium steel, encloses the shallow chamber in the top 60, 25 at its center rests upon the disc 61 and at its circumference rests upon the rim of the flange of the top. A vertical tubular reservoir casing 64, positioned above and to the right of the casing 48, is supported by 30 brackets 65, secured to the side wall of the compartment 47, so as to be spaced away from the wall. A head 66, enclosing the top of the casing 64, has a central vertical charging passage therethrough and a smaller 35 transmitting passage extending upward and then to the left through an extension of the head. A narrow transmitting pipe 67, bent so as to form a right angle at the top, is secured at one end by a coupling 68 to the 40 threaded left end of the extension of the head 66 and is secured at the lower end by a coupling 69 to the threaded upward extension of a flanged casing 70 that covers the diaphragm 63. Bolts 71 clamp the 45 circumference of the diaphragm 63 between the rims of the top 60 and the casing 70. A flanged extension 72 is secured to the lower end of the casing 64 and is closed on the under side by a thin metal diaphragm 73.

50 A flanged casing 74 is secured by bolts 75 to the extension 72 so as to clamp the circumference of the diaphragm 73. Within the casing 74 is a foot 76, having a threaded axial opening therethrough and having a 55 flange secured to and bearing upward upon the center of the diaphragm 73. A regulating screw 77 is provided for the greater portion of its length with right hand threads 78, of a slight pitch, and at its upper end 60 is of reduced diameter and is there provided

with left hand threads, of a greater pitch. The screw 77 is adapted to screw up and down, by means of its threads 78, in a threaded opening at the axial center of the lower end of the casing 74 and to screw up 70 and down, in the reverse direction, by means of its threads 79, in the axial central opening in the foot 76, the head of the screw extending downward below the casing for this purpose. A flanged extension 80, secured to the head 66 and having an axial passage in alignment with the charging passage of the head, is enclosed on top by a thin metal relief diaphragm 81, adapted to rest on the extension, and is internally 75 threaded above the diaphragm. A flanged stem 82 has its flange bearing downward upon the center of the diaphragm 81 and is surrounded above its flange by a strong compression spring 83, that is stronger than the 80 spring 62. A flanged clamping member 84 at its flange screws into the threaded part of the extension 80 so as to clamp the circumference of the diaphragm 81, loosely surrounds the spring 83 and the flange of the 85 stem 82, and is internally threaded on top. A head 85 screws into the threaded top of the member 84, surrounds the upper part of the spring 83, bears upon the top of the spring and has a vertical axial opening at 90 the top through which the upper end of the stem 82 may reciprocate.

Before the diaphragm 80 is clamped into position, some non-freezing liquid of a high coefficient of expansion, such as benzene 100 or alcohol, which may be called the thermostatic liquid, is introduced through the charging passage of the head 66 so as to fill the space enclosed thereby and by the parts 73, 72, 64, 67, 70 and 63. The parts 62—85 105 and the contained liquid constitute one form of refrigerator thermostat 86. Within the compartment 53 is a thermostat 87 cooperating with a valve in the casing 54 similar to the valve 59.

110 It is evident that the spring 62, bearing upon the disc 61, always tends to close the valve 59. When the thermostat is filled with liquid the capacity thereof is regulated by means of the screw 77. When the screw 77 115 is turned clockwise, the diaphragm 73 is drawn outward so as to increase the capacity of the containing walls and, the volume of the contained liquid remaining constant, to increase the closing tendency of the spring 120 62; but when the screw is turned counterclockwise, the diaphragm is forced inward so as to decrease the capacity of the containing walls and, the volume of the contained liquid remaining constant, to decrease the 125 closing tendency of the spring. Suppose a refrigerating process is beginning in the compartment 47 with an adjustment by the screw 77 such that the valve 59 is fully open. Under such circumstances, the disc 61 is in its 130

lowest position and bears down upon the contiguous part of the top 60. If the screw 77 has been turned too much counter-clockwise, with the disc 61 bearing upon the top 5 60, the diaphragm 81 has risen and, in opposition to the spring 83, has forced the stem 82 upward so that its top appears a greater or less distance above the head 85, thus serving as an indicator. As the refrigerating 10 process progresses, the thermostatic liquid contracts, the spring 83 forces the stem 82 and the diaphragm 81 to their lowest positions, and finally the spring 62 more or less completely closes the valve 59. But if, as 15 will be shown, the medium for refrigerating the compartment 47 has been passing the valve 59 during the refrigerating process assumed, then, as the valve tends to close, the supply of refrigerating medium is so 20 throttled that the tendency toward a cooling down of the compartment is counteracted. An equilibrium is thus established and the compartment 47, so long as the flow of refrigerating medium continues, is kept at such 25 temperature as has been determined by the adjustment of the screw 77. If, for any cause, the flow of refrigerating medium past the valve 59 should cease, then the temperature of the compartment 47 would tend to 30 rise to that of the outside atmosphere and the thermostatic liquid would expand first so as to open the valve 59 to the limit permitted by the disc 61 and second so as to force the stem 82 upward, in opposition to 35 the spring 83, thus preventing a bursting of the containing walls of the thermostat.

From the T. 44 a suction pipe 88 leads to the suction valve of a compressor 89. The piping 3 discharges into the water jacket of 40 the compressor 89 and a waste pipe 90 discharges from the opposite upper part of the water jacket. From a generator 91 a wire 92 leads to the upper one of a series of contacts 93 connected to one another by divisional or sub-resistances. An arm 94 is pivoted near its left end, but is insulated from the pivot; it is pivoted near its center to a solenoid core 95, but is insulated therefrom; and at its right end it operates, upon 45 the energization of the core, to make contact with the contacts 93, in ascending order, so as to cut out the resistances between the contacts successively. A dash pot device 96 is pivoted to the left end of the arm 94 and is operative to retard the upward movement of the right end of the arm. From the arm 94, near its pivot, a wire 97 leads to an electric motor 98, belt connected for driving the compressor 89, and from the motor a wire 50 99 leads through a point 100 back to the generator 93. From the wire 92 a wire 101 leads to a resistance 102, leading to a point 103. From the point 103 a wire 104 leads to a contact 105. From the upper end of a 55 switch 106 (best shown in Fig. 3), pivoted

at the center and with the upper end insulated from the lower part, a wire 107 leads to a split sliding contact post 108, secured to the under side of but insulated from a bracket 109. A pivot post 110 is secured to the under side of the bracket 109, a little to the left of the post 108, and is insulated from the bracket. From the post 110 a wire 111 leads to a contact block 112, secured to the under side of a bracket 113, but insulated therefrom. A contact block 114 is secured to the under side of the bracket 113, a little to the left of the block 112, and is insulated from the bracket. From the block 114 a wire 115 leads to a solenoid winding 116, adapted to energize the core 95. From the winding 116 a wire 117 leads to the point 100. Secured at its lower end to the flat head of the bellows 16 is a rod 118, adapted to reciprocate in a guide 119 and carrying above 85 its insulated top a switch 120, adapted to make contact with the contacts 112 and 114 and to connect them. A helical compression spring 121 surrounds the rod 118, at its upper end bears upon the under side of the 90 guide 119 and at its lower end bears upon the upper side of a nut 122, threaded upon the rod and secured in place by a lock nut 123. The spring 121 always tends to open the switch 120, but yields to an upward 95 movement of the head of the bellows 16 so as to permit of a closing of the switch.

A switch arm 124 is pivoted to the lower end of the post 110; it is adapted, as shown, when elevated to make a sliding contact 100 within the split parts at the lower end of the post 108; it has an insulated section just to the right of the post; it has a catch at its right end; and it has a depending handle near its right end. An angle bracket 105 125 is secured to the under side of the bracket 109, to the right of the post 108. A bell crank lever 126 is pivoted to the vertical part of the bracket 125; it has a horizontal arm extending to the right and situated so that the right end is in the path of the left end of the lever 36 or 36^a, as the case may be, when ascending; it has a depending vertical arm with a catch on the left side at the lower end adapted to engage the right end of the arm 124 and to hold it in contact with the post 108, as shown; and it has projecting to the left above the arm a finger adapted to bear down upon the arm when the lever 36 or 36^a, as the case may 110 be, bears upward against the horizontal arm. A flat spring 127, secured to the horizontal part of the bracket 125, bears upon the upper right end of the horizontal arm of the lever 126 so as to tend to rotate 115 the lever clockwise. When the lever 126 is rotated counter-clockwise, in opposition to the spring 127, the arm 124 is disengaged and, under force of gravity assisted by the finger of the arm, it drops out of contact 120 125 130.

with the post 108, thus opening the switch, but is stopped from dropping too far by a pin 128.

In Fig. 1, as distinguished from Fig. 3, 5 from the point 103 a wire 129 leads to the pivoted upper end of a thermostatic blade 130. The blade 130 is constructed, in the usual manner, of two flat strips, secured together, of materials having greatly unequal 10 coefficients of expansion, so that, with a pre-determined rise of temperature, its free lower end will make contact with an adjustable high temperature contact 131, and, with a predetermined fall of temperature, 15 the lower end will make contact with an adjustable low temperature contact 132. From the contact 131 a wire 133 leads to the winding 21^x; from the winding 21^x a wire 134 leads to the winding 21^y; and from the winding 20 21^y a wire 135 leads to the fixed end of a spring circuit closer 136. From the contact 132 a wire 137 leads to the winding 40^x; from the winding 40^x a wire 138 leads to the winding 40^y; and from the winding 25 40^y a wire 139 leads to the fixed end of a spring circuit closer 140.

The parts 140—149, to be described, and the circuit closers 136 and 140 are to be understood to be a part of the construction 30 common to Figs. 1 and 3, being more particularly disclosed in the latter figure. The lower end of the switch 106 is pivotally connected to a double end solenoid core 141. From a contact 142 a wire 143 leads to and 35 from a solenoid winding 144, that surrounds the right end of the core 141, to a point 145. From a contact 146 a wire 147 leads to and from a solenoid winding 148, that surrounds the left end of the core 141, to the point 145. From the point 145 a wire 40 149 leads to the wire 99. When the winding 148 is energized, it moves the core 141 to the left so that the conductor upper end of the switch 106 is out of contact with the contact 105, as shown, and the left end of 45 the core forces the circuit closer 140 to the left and away from the contact 146, as shown, the circuit closer having by reason of its spring construction a tendency to return to the position of contact. But when 50 the winding 144 is energized, it moves the core 141 to the right so that the conductor upper end of the switch 106 makes contact with the contact 105 and the right end of 55 the core forces the circuit closer 136 away from a closed position, as shown, into a position away from the contact 142, this circuit breaker also having by reason of its spring construction a tendency to return to 60 the position of contact. The weight of the switch 106 and the core 141 is such and the friction of the core in sliding contact with the windings 144 and 148 is such that, after the winding 148 has been energized, the 65 switch and the core stay in the position

shown notwithstanding a slight tendency of the circuit closer 140 to push the core 141 to the right, and that, after the winding 144 has been energized, the switch and the core stay in the position to the right where 70 the circuit closer 136 is away from the contact 142 notwithstanding a slight tendency of the circuit closer 136 to push the core to the left.

The method of operation of the parts disclosed in Figs. 1, 2, 4, 6 and so much of 75 3 as is common therewith and with Fig. 1 is as follows: Assume that the contacts 131 and 132 are so adjusted that on a rise of 80 temperature to 36 degrees the blade 130 makes contact with the contact 131 and on a fall of temperature to 33 degrees the blade makes contact with the contact 132. Then, on a rise of temperature to 36 degrees, a current passes from the generator 91 85 through the parts 92, 101, 102, 103, 129, 130, 131, 133, 21^x, 134, 21^y, 135, 136, 142, 143, 144, 145, 149 and 99 back to the generator. The energization of the windings 21^x and 21^y opens the valves 37 and 38, which are 90 so constructed as to remain open after such energization has ceased. And the energization of the winding 144 moves the core 141 to the right so as to close the switch 106 upon the contact 105, to permit the circuit 95 closer 140 to make contact with the contact 146 and to open the circuit closer 136. Consequently, when, on a subsequent cooling down of the compartment 41 below 36 degrees, the blade 130 leaves the contact 141, 100 there will be no prolongation of contact and no wearing away of the parts.

With the opening of the valve 37, assuming a full supply of water is available, water flows through the parts 11, 12, 13, 14, 15, 3 105 and 90, thus taking up heat from the ammonia in the tank 1 and from the water jacket of the compressor 89. But since the capacity of the pipe 13 is less than the capacity 110 of the pipe 11 and the valve 37, the casing 11 and the bellows 16 fill up so that the pressure of the water, in opposition to the spring 121, closes the switch 120. Thereupon a current passes from the generator 91 through the parts 92, 101, 102, 103, 104, 105, 106, 107, 115 108, 124, 110, 111, 112, 120, 114, 115, 116, 117, 100 and 99 back to the generator. The energization of the winding 116 closes the arm 94 upon the contacts 93, beginning with the lowest, until eventually all the divisional resistances are cut out. With the closing of the lowest contact 93, a current passes from the generator 91 through the wire 92, the contacts 93 and their divisional resistances, the arm 94 and the wire 97 to the motor 98 125 120 and thence through the wire 99 back to the generator; and, with a cutting out of all the divisional resistances, the full current is passing to the motor. Thereupon the motor 98 operates the compressor 89 so as to draw 130

expanded ammonia from the pipe 88 and to force it through the pipe 4 into the tank 1. It is evident that the motor 98 cannot start unless there is available a supply of water to fill the bellows 16.

With the opening of the valve 38, liquid ammonia from the tank 1 and the pipe 5 passes through the valve and the T 39 and thence in part through the pipe 40 to the valve 42. The valve 42, as is always the case with an automatic expansion valve, is set to correspond with the temperature to be maintained by the ammonia issuing and vaporizing therefrom. For a higher temperature the valve is set to permit a freer flow than for a lower temperature. The ammonia issuing from the valve 42 and vaporizing in the expansion chamber 43 takes up heat from the compartment 41 and affects the blade 130. The expanding ammonia from the expansion chamber 43 passes through the T 44 and thence through the pipe 88 into the compressor 89, as has been stated. But part of the liquid ammonia passes from the T 39 through the T 45, the pipe 46, the casing 48 and the pipe 49 to the valve 50. The ammonia issuing from the valve 50, and vaporizing in the expansion chamber 51, takes up heat from the compartment 47 and affects the thermostat 86; and finally, in an expanded condition, it passes through the T 44 and the pipe 88 into the compressor 89. And part of the liquid ammonia from the T 45 passes through the pipe 52, the casing 54 and the pipe 55 to the valve 56. The ammonia issuing from the valve 56, and vaporizing in the expansion chamber 57, takes up heat from the compartment 53 and affects the thermostat 87; and finally, in an expanded condition, it passes through the pipe 51, the T 44 and the pipe 88 into the compressor 89.

It is to be understood that the condenser is so proportioned that, under normal conditions of operation, the maximum flow of water through the piping thereof, even in the heat of summer, will be capable of liquefying under a non-excessive head pressure the maximum weight of hot ammonia gas forced into it per unit of time. Also in the cooler months of the year, or with a minimum weight of ammonia forced into the condenser per unit of time, a minimum flow of condensing water, that is to say a flow with the valve 17 in the position shown in Fig. 4, will suffice to prevent the head pressure from becoming excessive. Assume that the head pressure to be maintained is not to exceed say 160 pounds. Then, as the season advances and the water becomes warmer, or as a heavier duty is imposed upon the apparatus, the minimum flow of condensing water is insufficient to keep the head pressure below the limit assumed. Under such circumstances, with a proper adjustment of the

spring 27, as the head pressure rises to a few pounds less than 160 pounds, as indicated by the gage 2, the force exerted on the under side of the diaphragm 9 begins to lift it and to cause a wider opening of the valve 17, 70 as has been explained. Thereupon more water flows through the condenser piping and the head pressure tends to fall and to permit the spring 27 to exert the maximum throttling effect. An equilibrium is thus established so as normally to maintain the predetermined head pressure. Obviously this tendency of the head pressure to rise may be so great as to result in an opening of the valve 17 to the maximum. The primary 80 adjustment of the thrust of the spring 27 is made by means of the bolt 28 and the nut 29 and the secondary adjustment, so as to maintain the particular head pressure desired, is made by turning the bolt 21 and the locknut 22 up or down. After the primary adjustment has been made, the cap 30 and the casing 24 would properly be sealed, as has been indicated, and then any operator of the apparatus would be free to make such secondary adjustment as might be desired. 90

When, in the course of operation, the temperature in the compartment 41 falls to 33 degrees, the blade 130 makes contact with the contact 132. Thereupon a current passes from the generator 91 through the parts 92, 101, 102, 103, 129, 130, 132, 137, 40^x, 138, 40^y, 139, 140, 146, 147, 148, 145, 149 and 99 back to the generator. The energization of the windings 40^x and 40^y closes the valves 37 and 38, which are so constructed. And the energization of the winding 148 moves the core 141 to the left, as shown, so as to open the switch 106, to permit the circuit closer 136 to make contact with the contact 142 and to open the circuit closer 140. Consequently, when, on the ensuing rise of temperature in the compartment 41, the blade 130 leaves the contact 132, there will be no prolongation of contact and no wearing away of the parts. 11

With the opening of the switch 106, the current through the winding 116 ceases, the core 95 is de-energized, the arm 94 drops out of contact with the contacts 93, the current through the motor 98 ceases and the 11 motor and the compressor 89 begin to slow down, running, however, for a short time under their momentum and while so running continuing to force hot gas into the tank 1. With the closing of the valve 37, there is a 12 drop of the water level in the bellows 16 so as to open the switch 120; but water still continues to flow from the reservoir, composed of the parts 11-16, into the piping 3, so as to cool the gas entering the tank 1, before the compressor 89 stops entirely, until the supply in the reservoir is exhausted. Such supply, therefore, prevents an excessive head pressure while the compressor 89 is slowing down. With the closing of the 13

valve 38 the flow of liquid ammonia therefrom ceases.

Sometimes it will happen, before the blade 130 makes contact with the contact 132, that 5 there will be an accidental failure of the supply of water entering the valve 37. Under such circumstances there is a drop of the water level in the bellows 16 so as to open the switch 120 and to interrupt the current 10 through the winding 116. Such interruption has the same effect as does the opening of the switch 106 in stopping the compressor 89 and in affording a supply of condensing water while the compressor is running down. 15 But, upon a resumption of the water supply and a filling up of the bellows 16, the switch 120 closes and the operation of the apparatus is resumed in substantially the way that has been explained in reference to the starting 20 of the normal cycle. And sometimes it will happen, while the compressor 89 is running with a maximum flow of condensing water, that even such a flow does not prevent the head pressure from exceeding the predetermined limit. Such a condition may arise 25 in case the condenser is too small or is ill designed, or in case the condenser piping is allowed to become foul, or in case non-condensable gases become present in the upper 30 part of the tank 1. The head pressure might become high enough, from some such cause, as to open the valve 10 and thus to release the ammonia charge, or, in case such a valve were not provided, to cause an explosion of 35 the plant. But the emergency device, consisting of the parts 108—110 and 124—128 prevents any such consequence. For, after the condenser pressure has exceeded 160 pounds and the lever 36 has been entirely 40 lifted from the bolt 21, the ascending lever, say at 20 or 30 pounds higher pressure, such being the adjustment of the spring 27, trips the lever 126 and opens the switch arm 124, so as to interrupt the current through the 45 winding 116. Such interruption has the same effect as does the opening of the switch 106 or the opening of the switch 120 in stopping the compressor 89; but here the flow of condensing water continues indefinitely, with 50 the tendency of reducing the excessive head pressure. With the particular emergency device shown, which is essentially the same as that disclosed in Fig. 7 as modified by Fig. 17 of my aforesaid application Ser. No. 55 146,147, rather than that disclosed in Figs. 15 and 16 thereof, after a drop of the head pressure to normal, a manual act is necessary to close the arm 124, as by moving its handle clockwise. Such a manual act is intended to 60 occur after an investigation and a removal of the cause of the abnormal pressure. By the employment of the emergency device, it results that the valve 10 will open only in case of a fire involving the plant.

65 With the compartments 41, 47 and 53 of

the same size and with the refrigerating capacity of the expansion chamber 57 greater than that of the expansion chamber 51 and that of the latter greater than that of the expansion chamber 43, all other material conditions being substantially the same, assume that it is desired to maintain some certain temperature in the compartments 47 and 53. It may be here stated that the automatic expansion valves 42, 50 and 75 56 are simply automatic reducing valves, so constructed as to regulate the flow of ammonia therefrom, and thereby to maintain the pressure in the piping leading therefrom at a predetermined limit and thus to 80 predetermine the temperature within the piping; and that the advantage of such valves over the ordinary hand valves is that frequent manual adjustments to secure these results are rendered unnecessary. The temperatures in the compartments 41, 47 and 53 tend to approximate the temperatures produced by the vaporization of the ammonia in the expansion chambers 43, 51 and 57, respectively. Such tendencies, if unchecked, would result in too low temperatures. In the case of the compartment 41, the tendency toward too low a temperature is counteracted by the stopping of the compressor 89 when the blade 130 makes contact with the contact 132. But under the conditions stated, before the blade 130 could make contact with the contact 132, the temperatures in the compartments 47 and 53 would fall too low. Accordingly the thermostats 86 and 87 are adjusted so as to prevent such results, the screw 77 being used for that purpose, and to this end they operate as will now be explained. As the thermostatic fluid in the thermostat 86 begins to contract, the valve 59 tends to close and thus to throttle the flow of liquid ammonia to the valve 50. At first such a throttling, by lessening the supply, may decrease the pressure of the vaporizing ammonia 100 issuing from the valve 50 and thus may actually increase the refrigerating effect in the compartment 47. But it is evident that, as the throttling continues, after a brief time the supply is so diminished that, even 105 although the temperature in the expansion chamber 51 tends to become very cold, there is so little ammonia to vaporize therein that such tendency is counteracted by the rising 110 tendency of the temperature in the compartment 47. An equilibrium is thus established so that the temperature in the compartment 47 is kept to its predetermined low limit, until the blade 130 makes contact 115 with the contact 132 and the entire process of refrigeration is suspended. In the compartment 53 the only difference in operation 120 is that the thermostat 87, under the conditions assumed, begins to exert its throttling effect before the thermostat 86 begins to act. 125 130

It is obvious that the sizes of the compartments 41, 47 and 53 are only one factor in determining the refrigeration requirements therefor. Other factors are the temperatures to be maintained, the quality and thickness of the insulation, the weight and the specific heat of the contents of the compartments, the frequency with which the contents are renewed, and the like. The general rule therefore is this: For secondary compartments, such as the compartments 47 and 53, in parallel with the master compartment 41, the refrigerating capacities of the secondary expansion chambers in each, such as the expansion chambers 51 and 57, should be such that they will be capable of cooling down the secondary compartments to their predetermined low limits, while the apparatus is in active operation, before the master expansion chamber 43 can cool down the master compartment to its predetermined low limit.

With the stationary parts positioned as shown in Fig. 4, for a thermostatic control of the starting and stopping of the compressor 89, the flow and the non-flow of water into the pipe 11, by some such means as is herein disclosed, is necessary. On the other hand, the valve 38 is only of slight utility. For, when the compressor 89 is standing idle, while the temperature in the compartment 41 is rising from 33 to 36 degrees, there is always a tendency of the ammonia from the high pressure side to leak into the expansion chambers, also spoken of as the low pressure side, and thereby to cause a rise of pressure therein. Such a leakage may be backward through the discharge and suction valves of the compressor 89 or it may be forward through the valves 42, 50 and 56, if any such valve becomes worn. Such a condition of high pressure puts a strain upon that part of the apparatus that was designed to withstand only a low pressure. Furthermore, when, on a rise of temperature in the compartment 41 from 33 to 36 degrees, the compressor 89 again starts, at first it is occupied, with a waste of power, in pumping down the expansion chambers 43, 51 and 57 so as to produce low enough pressures to permit of vaporization therein. And it is apparent that, even with the valve 38 very close to the valves 40, 50 and 56 and preventing leakage from the pipe 5 therethrough, the valve 38 is incapable of preventing a back flow of ammonia through the discharge and suction valves of the compressor 89.

Secondly, considering the construction of Figs. 2, 3, 5, 6, 7 and so much of Fig. 1 as is applicable thereto: In Fig. 7 a hand switch 150 is interposed in the wire 92, by means of which the apparatus may be placed within or withdrawn from the thermostatic control thereof. The parts 93, 94, 95, 96 and

116 constitute one form of self starting rheostat, commonly termed a self starter, any such rheostat being adapted to close the circuit of a motor, but tending to open the circuit. I am not to be understood as being limited to any particular form of such rheostat. The wire 97 leads to a point 151 and the wire 99 leads from the point 100. From the point 151 a wire 152, as a series winding, leads, with the proper number of turns, around cores 153 and thence leads to an armature 154. From the armature 154 a wire 155 leads through a point 156 to the point 100. From the point 151 a wire 157 leads, as shown in Fig. 3, to a series of contacts 158, which for convenience of illustration are shown to be eight in number. Counting from the left, between the first four of the contacts 158 are divisional resistances 159 and between the fourth and the subsequent four are other divisional resistances 160. A hand switch 161 is so connected to two of the contacts 158 that when closed, as shown, it short circuits such of the resistances 159 as are between the second and fourth contacts. But when the switch 161 is open, a current must pass through all the resistances 159. It is to be understood that the switch 161 may be so connected to the first and fourth contacts 158 as to short circuit, when closed, all the resistances 159 or it may be connected so as to short circuit certain of the resistances in any other combination. A switch 162 at its upper end is shown in contact with the eighth contact 158 and is adapted to make contact with the fourth contact, after having cut out all the resistances 160. If so desired, the contacts 158 may be so positioned that the switch 162 will make successive contacts with any other two of the eight. From the switch 162 a wire 163 leads to the upper end of contacts 164, arranged in descending order and connected with one another by divisional resistances 165. The contacts 164 are so positioned that the conductor 36^a, when the lever 36^a ascends, will make contact with the contacts successively and will cut out the resistances 165 successively. From the lower one of the contacts 164 a wire 166 leads to a point 167, shown in Fig. 7. From the point 167, two wires 168 and 169, as field windings, with the proper number of turns, in parallel with each other, lead around the cores 153, each wire leading around half of the cores, to a point 170. From the point 170 a wire 171 leads to the point 156. The parts 152, 153, 154, 155, 167, 168, 169 and 170 thus constitute part of a cumulative compound motor 172, that is to be understood to be connected for driving the compressor 89.

Together with the switch 162, the parts 173, 174, 175, 176, 177, 178, 179, 189 and 181 are identical in construction and opera-

tion with the parts 106, 136, 142, 143, 144, 141, 140, 146, 147 and 148, respectively, except that the wires 175 and 180 lead to the wire 149.

5 A master refrigerator thermostat 182, shown in Fig. 3 and more in detail in Fig. 5, has as the basis of its construction an ordinary Bourdon tube pressure gage, such as the gage 2, adapted to measure the pressures either of ammonia or of sulphur dioxide, as may be preferred. A short tube 183 is to be understood to be connected with the fixed end of the Bourdon tube and to contain a little liquid ammonia or sulphur dioxide, as the case may be, so that, upon a rise of temperature and vapor pressure in the Bourdon tube, by means of the familiar mechanism employed in such gages, the free end of the Bourdon tube will rotate clockwise 15 a switch 184, similar to the pointer on such gages, and, upon a fall of such temperature and pressure, the free end will rotate the switch counter-clockwise. The switch 184 is insulated from a rotating 20 shaft 185 therefor and is positioned in front of an insulating face plate 186. From the point 103 the wire 129, properly insulated, leads to the fixed end of the switch 184. The plate 186 has, arranged in a circle 25 near its circumference, screw holes 187, a short distance apart from one another and extending part way through the plate. A long arc shaped high temperature starting contact 188 is detachably secured to the 30 plate 186, on the right hand side, by screws 189, screwing into certain of the holes 187. A comparatively short arc shaped piece 190 is detachably secured to the plate 186, on the left, by screws 191, screwing similarly 35 into certain of the holes 187; at the top it consists of a narrow low speed contact 192; and, for most of its length, it consists of a low temperature stopping contact 193, insulated from the contact 192. The free end 40 of the switch 184 is shown in a middle position between the contacts 192 and 188. Assume that the tube 183 contains a small quantity of liquid ammonia. Let it be assumed that the switch 184, as will be explained, is to start the compressor 89 at a 45 temperature of 37 degrees and to stop it at a temperature of 33 degrees. For a temperature of 37 degrees the corresponding ammonia vapor pressure is 54 pounds gage; 50 and for a temperature of 33 degrees, 48.6 pounds gage. The contact 188 is therefore positioned, by means of the screws 189, so that the switch 184 will make a sliding contact with the left end of the contact at 55 an ammonia vapor pressure of 54 pounds. And the piece 190 is positioned, by means of the screws 191, so that the switch 184 will make a sliding contact with the right end of the contact 193 at an ammonia vapor 60 pressure of 48.6 pounds. The contact 192

is so narrow and the insulation between it and the contact 193 is so narrow that, upon a movement of the switch 184 counter-clockwise, it will first make a sliding contact with the contact 192 at a pressure of 50 70 pounds, corresponding to a temperature of 34 degrees. The circular length of the contact 188 is so great that the switch 184 will be in contact therewith at any temperature between 37 degrees and the maximum atmospheric temperature, thus causing the thermostat 182 to be operative when it is desired initially to start the compressor 89 with a temperature inside the compartment 41 as high as the outside temperature. 80 Similarly the circular length of the contact 193 is so great that the switch 184 will be in contact therewith between 33 degrees and the lowest temperature that can be produced in the compartment 41, thus causing the 85 thermostat 182 to be always operative to stop the compressor 89 even although some other part of the apparatus might fail to act in effecting such stopping.

From the contact 188 a wire 194 leads to 90 the pivoted end of a hand switch 195. The wire 133 leads from a contact 196 to the winding 21^x, as before. From the winding 21^y the wire 135 leads to a contact 197. The switch 195 is shown in contact with the contact 197, but it may be turned into contact with the contact 196. From the contact 197 a wire 198 leads to a point 199. From the point 199 one wire 200 leads to the fixed end of the circuit closer 136 and another 100 wire 201 leads to the fixed end of the circuit closer 178. From the contact 192 a wire 202 leads to the fixed end of the circuit closer 173. From the contact 193 a wire 203 leads to the pivoted end of a hand 105 switch 204. The wire 137 leads from a contact 205 to the winding 40^x, as before. From the winding 40^y the wire 139 leads to a contact 206. The switch 204 is shown in contact with the contact 206, but it may be 110 turned into contact with the contact 205. From the contact 206 a wire 207 leads to the fixed end of the circuit closer 140. I am not limited to the particular kind of thermostat 182 above described. Any thermostat 115 having a starting contact, a stopping contact and an intermediate low speed contact will accomplish my purpose.

The method of operation of the parts disclosed in Figs. 2, 3, 5, 6 and 7 and so much 120 of Fig. 1 as is applicable thereto is as follows: It is assumed that the thermostat 182 replaces the parts 130, 131 and 132 in the compartment 41 and that the valves 37 and 38 have been operated so as now to be open. For it will appear that the valves 37 and 38 are not essential to the present construction, the possibility of their omission being one of the advantages of the present construction. On a rise of temperature in the 130

compartment 41 to 37 degrees, a current passes from the generator 91 through the parts 101, 102, 103, 129, 184, 188, 194, 195, 197, 198, 199, 200, 136, 142, 143, 144 145 and 149 back to the generator. The energization of the winding 144 moves the core 141 to the right so as to close the switch 106 upon the contact 105 to permit the circuit closer 140 to make contact with the contact 146 and to open the circuit closer 136. Consequently, when, on a subsequent cooling down of the compartment 41 below 37 degrees, the switch 184 leaves the contact 188, there will be no prolongation of contact and no burning away of the parts.

There being a free inflow through the pipe 11, assuming that there is no accidental failure of the water supply, the switch 120 is in a closed position; and this is so whether the valve 17 is open, as previously considered, or is closed, as shown. With the closing of the switch 106 there is the same closing of the arm 94 upon the contacts 93, with a cutting out of the divisional resistances, that has been described already. Thereupon a current passes from the generator 91 through the wire 92, the arm 94, the wire 97 and the point 151 and thence in part through the winding 152, the armature 154, the wire 155, the points 156 and 100 and the wire 99 back to the generator. But from the point 151 a part of the current passes through the wire 157, some of the contacts 158, part of the resistances 159, the switch 161, the resistances 160, the switch 162, the wire 163, the contacts 164, the resistances 165, the wire 166, the point 167, the windings 168 and 169, the point 170, the wire 171, the point 156 and the wire 99 back to the generator. The motor 172 and the compressor 89 start the process of refrigeration in the compartments 41, 47 and 53, as before.

Whether the valve 17 is open or shut when the motor 172 starts depends upon the atmospheric temperature outside of the tank 1. To maintain a head pressure of 160 pounds, it is necessary that the valve 17 should begin to open say at 150 pounds pressure. A temperature of 84 degrees outside of the tank 1 and hence also within the tank corresponds to a pressure of 150 pounds for the ammonia vapor therein. Consequently, if a head pressure of 160 pounds is to be maintained, whenever the outside temperature is at or above 84 degrees, there will be a flow of condensing water whether the compressor 89 is running or is standing idle. But, whether the valve 17 is open or shut, as hot gas is forced into the tank 1, the pressure on the under side of the diaphragm 9 forces it upward so as to cause a further opening of the valve 17 and the maintaining of an equilibrium, as before. If, in the warmer months of the year, it is desired

to prevent a waste of the condensing water, while the compressor 89 is standing idle, the switches 195 and 204 may be turned into contact with the contacts 196 and 205, respectively, so that the valve 37 (and the valve 38, if retained) will operate as before.

When, in the course of operation, the temperature in the compartment 41 falls to 34 degrees, the switch 184 makes contact with the contact 192. Thereupon a current passes from the generator 91 through the parts 101, 102, 103, 129, 184, 192, 202, 173, 174, 175, 176 and 149 back to the generator. The energization of the winding 176 moves the core 177 to the right so as to move the switch 162 from contact with the eighth contact 158 into contact with the fourth contact to cut out the resistances 160, to permit the circuit closer 178 to make contact with the contact 179 and to open the circuit closer 173. In consequence of the opening of the circuit closer 173, it will happen that, when the switch 184 leaves, in either direction, the contact 192, there will be no prolongation of contact and no burning away of the parts. The cutting out of the resistances 160 strengthens the field and causes an increase of the counter electromotive force of the motor 172 so that its speed and the speed of the compressor 89 decrease. Consequently less ammonia per unit of time is circulated through the expansion chambers 43, 51 and 53 and the temperature in the compartment 41 may tend to rise. Under such circumstances, either one of two results will happen. First: There may be a rise of temperature in the compartment 41 so as to cause the switch 184 to make contact with the contact 188. Thereupon, as at the starting, a current from the generator 91 passes to the point 199; but, the circuit closer 136 being open, from the point 199, the current passes through the parts 201, 178, 179, 180 and 149 back to the generator. The energization of the winding 181 moves the core 177 to the left so as to move the switch 162 back into contact with the eighth contact 158, to throw in the resistances 160, to permit the circuit closer 173 to make contact with the contact 174 and to open the circuit closer 178 thus restoring the parts to their original position. The throwing in of the resistances 160 weakens the field and causes a decrease of the counter electromotive force of the motor 172 so that its speed and the speed of the compressor 89 increase. Consequently more ammonia per unit of time is circulated through the expansion chambers 43, 51 and 53 and the temperature in the compartment 41 will fall to 34 degrees, with the same effect as before. This changing from full speed to low speed and the reverse, according to the temperature requirements of the compartment 41, is the ideal condition. For it is apparent that

with a change of the motor 172 from low speed to full speed there can be no such waste of power as there is when a dead motor is started up. The extent to which the resistances in line with the field windings 168 and 169 can be cut out may be varied by opening or closing the switch 161 and by changing its connections with certain other of the contacts 158, as has been indicated. These variations may be made with the progress of the seasons or as the duty imposed on the apparatus increases or diminishes in consequence of its particular employment. But, second, it may happen that, notwithstanding the cutting out of the resistances 160, the temperature in the compartment 41 may continue to fall, reaching 33 degrees. Thereupon, as the switch 184 makes contact with the contact 193, a current passes from the generator 91 through the parts 101, 102, 103, 129, 184, 193, 203, 204, 206, 207, 140, 146, 148, 147 and 149 back to the generator. The energization of the winding 148 moves the core 141 to the left so as to open the switch 106, to permit the circuit closer 136 to make contact with the contact 142 and to open the circuit closer 140. Consequently, when, on the ensuing rise of temperature in the compartment 41, the switch 184 leaves the contact 193, there will be no prolongation of contact and no burning away of the parts.

With the opening of the switch 106, the motor 172 and the compressor 89 slow down and stop, as in the first construction. Unless there is a failure of the supply of condensing water, the switch 120 is continuously closed. If the head pressure is above 150 pounds, the valve 17 remains open until there is a sufficient drop of pressure to close it. And, as before, while the motor 172 and the compressor 89 are slowing down there is a supply of condensing water sufficient to prevent an excessive head pressure. But, if, as was possible, the switches 195 and 204 had been turned into contact with the contacts 196 and 205, respectively, the valve 37 (and the valve 38, if retained) close when the switch 184 makes contact with the contact 193 and the inflow of condensing water into the casing 12 is shut off.

On a rise of temperature in the compartment 41 to 34 degrees, the switch 184 makes contact with the contact 192, but normally there will be no actuation of the switch 162 because the circuit closer 173 is open; but, if, by reason of any accidental displacement of the parts (as was assumed to be the case in describing the starting), the circuit closer 173 should happen to be closed, as shown, the only effect would be to cut out the resistances 160, to close the circuit closer 178 and to open the circuit closer 173, or, in other words, to position the parts as they would be positioned in the absence of the accident.

On a further rise of temperature in the compartment 41 to 37 degrees, the switch 106 is closed and the motor 172 and the compressor 89 start up, as before. Furthermore—and this is the normal condition—a part of the current from the generator 91 through the point 199 passes through the parts 201, 178, 179, 180, 181 and 149 back to the generator, so that the energization of the winding 181 throws in the resistances 160, causes the closing of the circuit closer 173 and opens the circuit closer 178, as before. Consequently, when the starting rheostat has acted so as to transmit the full current to the motor 172, the compressor 89 is operating at its full capacity.

Sometimes it will happen, while the compressor is running, that there will be an accidental failure of the water supply entering the pipe 11. Under such circumstances there is a drop of the water pressure in the bellows 16 so as to open the switch 120 and to interrupt the current through the winding 116, thus stopping the compressor 89, as before. Upon a resumption of the supply and a sufficient rise of water in the bellows 16, the switch 120 closes and the control of the apparatus is restored to the thermostat 182. In this construction, therefore, as distinguished from the first construction, the switch 120 acts merely as a safety device.

In case the maximum flow of condensing water is insufficient in preventing the head pressure from exceeding the predetermined normal limit, say of 160 pounds, the lever 36^a ultimately may trip the lever 126 and stop the compressor 89, as has been described in reference to the lever 36 in the first construction. But here, before the lever 126 can be tripped, the conductor 36^b, as the lever 36^a ascends, makes contact with the contacts 164 successively and cuts out the resistances 165 successively. The effect is to strengthen the field and to cause an increase of the counter electromotive force of the motor 172 so that its speed and the speed of the compressor 89 decrease in the same manner as when the resistances 160 are cut out. The slowing down of the compressor 89 causes less ammonia to be forced into the tank 1 so that the head pressure may cease to rise and the lever may not be tripped at all. And if the head pressure should drop back to normal, the action in reference to the contacts 164 and the resistances 165 reverses, so that the compressor 89 resumes its full duty. Accordingly, both under the control of the temperature in the compartment 41 and under the control of excessive condenser pressure, the motor 172 operates as a variable speed motor and the compressor 89 operates as a variable speed compressor. There has not been, however, any attempt herein to illustrate a particular kind of motor adapted to the maximum reduction of speed by 130

the means herein disclosed. The particular motor shown is a cumulative compound motor. But I am not limited to any particular kind of motor nor to any particular means 5 for varying its speed.

Thirdly, considering the construction of Fig. 8 in connection with certain parts of the second form of construction: The defect of the means for varying the speed of the motor 172 in the second form of construction is that when the resistances 160 are cut out, so as to slow down the motor, the resistances 165 remain in series except in the very rare occurrence of an abnormal head pressure beyond the control of the maximum flow of condensing water. Therefore, under ordinary circumstances, the extent to which the motor 172 can be slowed down is much restricted. This difficulty is remedied in the 20 third form of construction. For convenience of illustration the contacts 164 are five in number and will be counted from the top. The resistances 165 are omitted. A contact 208 is below the fourth contact 158. The 25 wire 163 is disconnected from its former connections and now connects the eighth contact 158 and the contact 208. The fifth, sixth, seventh and eighth contacts 158 are so high as to be out of the path of the switch 162. The 30 sole function of the switch 162, when the winding 176 is energized, is to connect the fourth contact 158 and the contact 208; and, when the winding 181 is energized, it disconnects these contacts. A wire 209 connects the fourth contact 164 and the seventh contact 158; a wire 210 connects the third contact 164 and the sixth contact 158; a wire 211 connects the second contact 164 and the fifth contact 158; a wire 212 connects the first 35 contact 164 and the fourth contact 158; and a wire 213 connects the fifth contact 164 and the contact 208.

Consequently, when the switch 162 is out of connection with the contact 208, a current 40 may pass through the resistances 160, the contacts 158, the wire 163, the contact 208, the wire 213, the fifth contact 164 and the parts in series with these named parts. But, when the switch 162 connects the fourth contact 158 and the contact 208, the current will 45 pass through the fourth contact 158, the switch 162, the contact 208 and through the parts in series therewith, thus cutting out the resistances 160. And when the ascending conductor 36^b makes contact with the contacts 164 successively, beginning with the fifth, on making contact with the fourth contact 164, a current passes through the wire 209 and one quarter of the resistances 160 50 are cut out, on making contact with the third contact 164 a current passes through the wire 210 and one half of the resistances are cut out, on making contact with the second contact 164 a current passes through the wire 211 and three quarter of the resistances are 55

cut out and on making contact with the first contact 164 a current passes through the wire 212 and all the resistances are cut out. And this result happens quite independently of the position of the switch 162. By this preferred means of cutting out the resistances 160, the speed of the motor 172 can be very greatly reduced when either the thermostat 182 or the controller operates in relation thereto. By the low speed control of the 70 motor 172 there is greatly lessened the waste of power existing in the first construction in consequence of the starting up of the motor after each of its frequent stoppings and of the associated pumping down of the expansion chambers. And the motor 172 starts so rarely from a dead stop that the valve 38 75 may be omitted.

Fourthly, considering the construction of Fig. 9 in connection with certain parts of the prior construction: The pipe 11 leads into the lower left side of a reservoir casing 214 and the pipe 13 leads from the lower right side of the casing. A shaft 215 extends through the front wall of the casing 214; it has secured to its back end within the casing an arm ending in a float 216; and it has secured to its front end outside of the casing a lever 217, extending in a direction opposite to that of the interior arm. A cord 218 at 85 one end is secured to the free end of the lever 217; it passes upward over pulleys 219 and 220; it has at its depending other end a weight 221; and it has above the weight actuating buttons 222 and 223. A pivoted bell 100 crank lever 224 has an opening through the end of a lower arm extending to the right, through which opening passes the part of the cord 218 that is between the buttons 222 and 223; and it has a weight ball 225 at the end 105 of the other arm, extending upward. A stop 226 prevents the ball 225 from falling too far to the right and a stop 227 prevents the ball from falling too far to the left. A conductor section of the upper arm of the lever 110 224 is insulated at the top from the part that may rest upon the contacts 226 and 227 and also from the part near the pivot. When the ball 225 and the adjacent part of the arm rest upon the stop 227, the conductor section 115 is in contact with contacts 228 and 229, so as to connect them. The wire 111 leads to the conductor 228 and the wire 115 leads from the conductor 229.

This fourth construction may be used as 120 a substitute for the parts 12, 16, 112, 113, 114, 118, 119, 120, 121, 122 and 123 already considered. On a rise of the water level in the casing 214, the float 216 rises and depresses the lever 217 so as to pull the cord 125 218 over the pulleys 219 and 220 until the button 223 actuates the lever 224 into a position where the ball 225 is to the left of its vertical center. The ball 225 then drops, until the stop 227 prevents any further 130

movement, so that the conductor part of the upper arm of the lever 224 connects the contacts 228 and 229, thus having the same effect as does the closing of the switch 120. 5 On a subsequent drop of the water level in the casing 214, the float 216 falls and the weight 221 pulls the cord 218 over the pulleys 220 and 219 in a reverse direction until the button 222 actuates the lever 224 into a position where it breaks connection 10 between the contacts 228 and 229 as the ball 225 is pushed to the right of its vertical center and falls until stopped by the stop 226, thus having the same effect as does the 15 opening of the switch 120.

Finally considering the construction of Fig. 10: Here, by a transposition of the parts, the valve 50 is placed between the pipes 46 and 49 and the casing 48 and the 20 thermostat 86 are placed between the pipe 49 and the expansion chamber 51. A similar transposition may be made of the parts 54 and 87 and the part 56. Neither such arrangement is preferred over the prior 25 construction.

While the parts disclosed are adapted for use in connection one with another as has been described, yet many of the elements may be used in other connections. For example, the means for slowing down the 30 motor 172 in case of excessive condenser pressure and for speeding it up to normal upon a drop of pressure to normal may be used separately not merely in connection with a 35 manually controlled refrigerating machine but also in connection with any kind of electrically operated forcing means for forcing fluid into a container. So, also, the thermostatically controlled means for slowing down and speeding up the motor 172 40 may be used apart from the condenser pressure controlled means for so doing. So, also, the parallel feed system for one or a plurality of compartments associated with 45 a master compartment 41 may be used separately both with a manually started and stopped compression refrigerating machine and also with any kind of absorption refrigerating machine. The first form of construction is similar in principle to the form 50 of construction disclosed in my aforesaid application Ser. No. 126,019, as modified by the construction of Fig. 8 thereof, with the addition that by the present construction 55 an additional valve, such as the valve 38, can be thermostatically controlled.

I claim—

1. In combination, a refrigerating apparatus including a condenser, an expansion 60 chamber and a compressor in circuit, an electric motor for driving the compressor, and a thermostat at a high temperature limit operating the motor at full speed, at a medium temperature limit operating it at

low speed and at a low temperature limit 65 stopping it.

2. In combination, a refrigerating apparatus including a condenser, an expansion chamber and a compressor in circuit, electric means for driving the compressor, a 70 starting contact, a low speed contact, a stopping contact and a thermostat at a high temperature limit closing a circuit through the starting contact to operate the compressor at full speed, at a medium 75 temperature limit closing a circuit through the low speed contact to operate the compressor at low speed and at a low temperature limit closing a circuit through the stopping contact to stop the compressor. 80

3. In combination, a refrigerating apparatus including a condenser, an expansion chamber and a compressor in circuit, electric means for driving the compressor, a 85 starting contact, a low speed contact, a stopping contact, a conductor for engaging any of the contacts, a thermostat at a high temperature limit closing a circuit through the conductor and the starting contact to operate the compressor at full speed, at a medium temperature limit closing a circuit through the conductor and the low speed contact to operate the compressor at low speed and at a low temperature limit closing a circuit through the conductor and the 90 stopping contact to stop the compressor, and means breaking the current through the conductor and each contact upon the engagement thereof. 95

4. In a refrigerating system including 100 a condenser, an expansion chamber leading therefrom and a compressor leading from the chamber into the condenser, and temperature controlled means at a high temperature limit operating the compressor at full speed, at a medium temperature limit operating it at low speed and at a low temperature limit stopping it. 105

5. In a refrigerating system including 110 a condenser, an expansion chamber leading therefrom and a compressor leading from the chamber into the condenser, an electric motor for driving the compressor and having a shunt winding and resistances in 115 series therewith, and temperature controlled means at a high temperature limit operating the motor at full speed, at a medium temperature limit cutting out certain of said resistances and at a low temperature 120 limit stopping the motor.

6. In a refrigerating system, a compartment, an expansion chamber therein, a condenser leading into the chamber, forcing means for drawing expanded refrigerant 125 from the chamber and forcing it into the condenser, and means controlled by the temperature of the compartment and varying

- the rate of operation of the forcing means according to the refrigeration requirements of the compartment but stopping said means at a low temperature limit.
- 5 7. In combination, a condenser, forcing means for forcing fluid into the condenser, controlling means for operating the forcing means either at full capacity or at part capacity, and means controlled by the head pressure to operate said means at part capacity in case such pressure becomes excessive.
- 10 8. In combination, a condenser, forcing means for forcing fluid into the condenser, controlling means for operating the forcing means either at full capacity or at part capacity, and means controlled by the head pressure to operate said means at part capacity in case such pressure becomes excessive and to stop said means on a further rise of pressure.
- 15 9. In combination, a condenser, a compressor leading into the condenser, controlling means for operating the compressor at full speed or at low speed, and means controlled by the head pressure to operate the compressor at low speed or at full speed with a rise or fall of such pressure.
- 20 10. In combination, a condenser, a compressor leading into the condenser, controlling means for operating the compressor at full speed or at low speed, and means controlled by the head pressure to operate the compressor at low speed or at full speed with a rise or fall of such pressure and to stop
- the compressor in case of a high excessive pressure.
11. In combination, a condenser, electrically operated forcing means for forcing fluid into the condenser, and means controlled by the head pressure to vary the rate of operation of the forcing means according to the variations of such pressure.
12. In combination, a condenser, electrically operated forcing means for forcing fluid into the condenser, and means controlled by the head pressure to vary the rate of operation of the forcing means according to the variations of such pressure and stopping said means in case of a high excessive pressure.
13. In combination, a condenser, a compressor leading into the condenser, an electric motor for driving the compressor, and means controlled by the head pressure to run the motor at low speed or at full speed with a rise or fall of such pressure.
14. In combination, a condenser, a compressor leading into the condenser, an electric motor for driving the compressor, and means controlled by the head pressure to run the motor at low speed or at full speed with a rise or fall of such pressure and to stop the motor in case of a high excessive pressure.
